UNITED STATES PATENT OFFICE.

JOSEPH R. JACKSON, JR., OF BOSTON, MASSACHUSETTS, ASSIGNOR TO A. B. LEE ELEVATOR COMPANY, INC., OF NEW YORK, N. Y., A CORPORATION OF DELAWARE.

ELEVATOR SYSTEM.

Application filed February 27, 1924. Serial No. 695,491.

This invention aims to improve elevator systems and more particularly, though not exclusively, the door or closure operating instrumentalities therefor.

5 In the accompanying drawings showing one embodiment of my invention:

Fig. 1 is a front elevation of an elevator car showing a portion of the elevator shaft door in elevation with parts thereof broken away to more clearly illustrate the operating means therefor and the closure means for the car;

Fig. 2 is a detail vertical section taken substantially on the line 2—2 of Fig. 1 illustrating an example of interlocking means whereby movement of one closure is effected from movement of the other;

Fig. 3 is a detail front view of the interlocking means of Fig. 2;

20 Fig. 4 is a detail vertical section taken on the line 4—4 of Fig. 1 showing power actuated means operating the elevator closure means; and

Fig. 5 is a detailed side elevation of the 25 power unit from which power is received to operate the aforesaid means.

This invention is primarily, though not exclusively, concerned with the providing of power means to be operated when the elevator car is in a predetermined relation to closure or barrier means for elevator shaft openings to supplement or cooperate with manually operable door or closure operating instrumentalities already installed upon the 35 doors for the several floors served by the elevator car and also to operate the closing means for the car itself.

In the drawings, an elevator car 1 is illustrated which may be provided with any appropriate motive power to move the same to loading and unloading relation with the several floor openings served by said car.

The opening of the elevator car through which the passengers enter or leave the car 45 is provided with closure means herein consisting of a folding gate 2 supported by rollers 3 engaging a suitable track at the top of the car 1.

The elevator car 1 is arranged to operate 50 in the usual manner in a well or shaft 5 having openings such as that shown at 6 at the various floor levels served by said car, said openings being guarded by barriers preferably consisting of doors 7 formed in one or

more relatively sliding sections according to 55 the width of the openings required but herein said door is composed of two sections 8 and 9, the section 8 being arranged to slide by the section 9 to provide an opening substantially the size of the opening of the elevator car protected by said gate 2.

The doors 8 and 9 for the elevator shaft openings are preferably arranged to be manually operated and herein by means consisting of links 11 and 12 pivotally connected 65 together at 13. The link 11 is pivotally secured at its other end at 14 to a portion of the sliding section 8 of said door and the farther end of the link 12 is desirably pivotally secured at 15 to a fixed bracket 16. 70 An operating arm 17 is provided for one of said links, preferably the link 11 whereby said links 11 and 12 which constitute a toggle, may be buckled or broken and, by so doing, move the section 8 of the door to its open position, appropriate stops being provided to insure the alignment of the links 11 and 12 in their straightened door closing relation shown in Fig. 1 to prevent opening 75 of said doors without first tilting said links. 80

For convenience self-closing means are provided herein consisting of a cylinder 18 pivoted at 19 to a fixed part of the elevator shaft. A piston 20 is arranged in the cylinder 18 and is connected by a rod 21 with the link 12 near its pivot 15. Also arranged within the cylinder 18 between the piston and a cap 20^a secured to the end of the cylinder from which the rod 21 protrudes is a spring 22 which normally acts to force the piston 20 to the lower end of the cylinder 19, thereby causing the return of the links 11 and 12 to their straightened door locking positions. These links are mounted upon the inside of the doors 8 and 9 and in convenient relation to the opening in the elevator car when the latter is brought to a 90 position in front of said doors. 95

It is desirable at times to operate the doors 8 and 9 by power rather than by manual means; therefore I provide a power unit 23 herein for convenience mounted upon the car 1 to move therewith and preferably embodying in its construction an electric motor 24 secured to the frame 25 of the elevator 100 and having a worm 26 secured to its arbor to operate a worm gear 27. The worm gear 27 is secured to a shaft 28 journaled to rotate 105

in suitable bearings provided in a casing 29 enclosing said worm gear and worm, and to the end of the shaft 28 is secured crank disk 30 having a pin 31 to which a link 32 is attached. The link 32 is connected with and adapted to impart desired reciprocatory movements to a slide 33 arranged to slide in appropriate guides 34 herein secured to the outer side of the elevator 1 adjacent to the door 9.

Any appropriate means may be provided for communicating the movement of the slide 33 to the movable door section 8 but preferably for this purpose there is pivotally secured at 36 to the slide 33 a contact member 35 carrying at its free end a friction roll 37 adapted, at the proper time, to be swung into operative engagement with the link 12 (see Fig. 4) and to tilt said link, buckling the toggle formed by it and the lever 11 and thus causing the door to which the end 14 of said link 11 is attached to slide to its open position.

During the normal operation of the elevator car up or down in the shaft or well 5 it is desirable that the contact arm 35 be in its out-of-contact position so as not to interfere with the movements of the elevator until the floor of the car has been brought substantially in register with one of the floors of the shaft and it is desired to open the door for passengers to enter or leave the car.

To accomplish the proper positioning of the arm 35 and its friction roller 37 in operative relation to the link 12, said arm 35 is provided with a tail 38 arranged normally to extend beyond the rear face of the slide 33 and adapted, when in a certain position, to engage the end 39 of a relatively fixed cam plate 40.

The front face 41 of this plate is arranged to be engaged by a flat surface 42 formed upon said tail piece substantially at right angles to the long dimension of the contact arm 35, after said arm 35 has been swung outwardly to its link-engaging position from the full line position shown in Fig. 4 to the dotted line position therein. The engagement of the tail 38 with the end 39 of said plate, during the upward movement of the slide 33, together with said arm, causes said arm to be moved so that its flat surface 42 is in contacting and sliding relation with the face 41 of said cam plate, the initial movement of said slide being utilized for this purpose.

To soften the impact of the friction member 37 upon the link 12 said member 37 is resiliently mounted in the end of the arm 35 and yields slightly when the impact occurs. The throw of the crank 31 is preferably such that in addition to swinging the link 12 upwardly to its fully collapsed position when the arm 35 and friction rolls 37 are in operative relation thereto, the slide 33

will be moved a greater amount than is necessary to bring the tail 38 into engagement with the end 39 of the fixed cam plate 40 and to throw the arm 35 to its operative position against the link 12. This movement is effected in substantially one half a rotation of the disk 30, said disk however being permitted to rotate until the slide 33 is returned to its normal starting position where-in the contacting member 35 is out of engagement with the link 12.

The arrangement of the power driven or power operating instrumentalities is preferably such that even though the crank disk 30 makes a complete turn or moves the link 12 to its highest position and is then retracted to its normal starting position, the link 12 need not follow to its starting or door closing position until later.

In other words the present construction is arranged to move the link 12 upwardly but not to move it downwardly and the cylinder 18, piston 20 and spring 22 effect the self closing of the door independently of said power means.

The operator may, by maintaining pressure upon the operating lever, retain the door in its open position as long as he sees fit owing to the manner in which the link 12 is engaged by the actuating member 35, the latter half of the rotation of the crank disk 30 causing said actuating member merely to drop away from said link and after reaching the end of the plate 40 to retract to its inactive full line position of Fig. 4 allowing the elevator car to ascend and descend without interference therewith.

The member 35 is preferably, though not essentially, carried by the elevator car together with the power actuating instrumentalities 23. Therefore the car must be brought within a certain predetermined range of the elevator shaft opening 6, the door whereof is controlled by the manually operable lever mechanism including the links 11 and 12 whereby said actuated arm 35 will strike said link 12 upon its being thrown upwardly as hereinbefore described, but in order to allow for the careless positioning of the car with relation to said opening by the operator, a slightly greater throw of the crank pin 31 than is normally required may be and preferably is provided. For example the tail 38, in its lowermost position, is spaced from the end 39 of the plate 40 against which it contacts and this gap together with the movement required to swing the friction member 37 from its lower position shown in full lines in Fig. 4 to its dotted position of said figure provides for any reasonable variation between the floor level of the car and that of the floor at which a landing is to be made, whereupon the full opening of the door will be assured even though its initial opening

is advanced or retarded due to the variable stopping position of the car.

The variations which would apparently occur at the end of the door opening operations due to the delayed or advanced contact with the link 12 by the arm 35 may be provided for by allowing for a greater movement of the arm 35 than is normally required to move the door to its substantially full open position which position will be determined by appropriate stops or resilient bumpers of the usual type employed in all elevator doors but not shown herein. Should the elevator car be brought to a stop at a point above the threshold of the shaft opening and the upward movement of the carrier 33 be continued beyond the point where the door would normally strike the full open stops, the friction member 37 being resiliently mounted, as hereinbefore mentioned, will yield sufficiently by compressing the spring 43 interposed between the carrier for said friction member 37 and the arm 35 to absorb any reasonable excess movement of the opening means.

Within the scope and purpose of the invention the closure means, herein the gate 2, for the entrance and exit opening of the elevator car may be manually operated by the elevator operator but preferably means are provided for effecting the conjoint movement of said closure means and said door.

To this end means are preferably mounted upon a movable part of the elevator shaft door, herein the section 8, said means being normally retracted to a position wherein they will not interfere with the ascent or descent of the elevator car but when it is desired to open the closure means for the elevator car and said car is in proper alignment with a shaft opening, said means may be moved to a position such as to effect the interlocking of the movable door section 8 with the closure means 2 and thereby cause both of these parts to move together to their open positions.

Any appropriate device may be utilized for the purpose just described but herein I have shown mounted upon the door 8, a rocker arm 44 pivoted at 45 in a bracket 46 attached to said door and having, at its free end, a cross arm 47 carrying friction members 48. The arm 47 is pivotally mounted upon the end of said arm 48 and is adapted to be yieldingly held in operative position by a spring 49.

Movable with the arm 44 is a crank arm 50 connected by a link 51 with one arm 52 of a bell crank lever 53 pivoted at 54 to the door section 8. One arm 55 of said bell crank 53 is slotted at 56 and receives a pin 57 projecting laterally from a sliding rod 58, the latter arranged to slide in appropriate brackets 59 also carried by said door.

65 A spring 60 encircling said rod and respec-

tively bearing against a collar 61 and one of said bearings 59, normally urges the rod 58 toward the right of Fig. 3 and into yielding contact with the jamb 62 of the elevator shaft opening when the door section 8 is 70 closed.

The normal position of the member 44 and its cross arm 47, when the door 8 is closed, is that shown in dotted lines, Figs. 2 and 3, wherein the cross arm 47 rests in 75 engagement with a contact plate 63 upon the door 8. The plate 63 causes the cross arm 47 to be rocked upon the arm 44 to a position which places the spring 49 under tension and holds said cross arm substantially parallel with and flat against said plate. In this position the arm 47 is held by the rod 58 and connecting instrumentalities as long as the door section 8 remains closed and the said rod 58 remains with its 80 end substantially flush with the forward edge 62 of the door 8 and in contact with the edge 62 of the door jamb.

Mounted upon the closure means 2 is a channeled plate 64 having spaced and substantially parallel flanges 64¹, the extremities whereof are curved outwardly to form flaring mouths 65. The channeled member 64 is positioned upon the gate 2 at a point to receive between its flanges the cross arm 95 47 and its friction members 48 when the latter are swung to lateral position by the initial opening of the door section 8.

The flanges 64¹ are desirably long enough to receive the friction members 48 and their 100 carrying arm even though the elevator car floor be stopped slightly above or below the level of the floor at a selected opening 6 of the elevator shaft.

The transverse position of the channel 105 member 64 is preferably such that when the door 8 is opened just far enough to clear the end of the rod 58, as indicated at Fig. 3, said flanges will receive between them the two friction members 48 carried by the cross arm 110 47 as the latter are swung from their upper collapsed positions to the interlocking position thereof and following which continued movement of the door 8 will produce a like movement of said gate 2. In other words the 115 door 8 and the gate or closure means 2 will be moved conjointly from the point where the interlocking action takes place to the fully opened positions thereof.

A brief description of the general operation of the invention is as follows:

The elevator car is moved to the desired floor level and brought to a stop with the floor of said car either in perfect alignment with the floor of the opening 6 or within a predetermined range of said floor. The operator of the car then operates appropriate circuit controlling devices not shown energizing the electric circuit containing the motor 24 which causes said motor to revolve 120 125 130

- the crank disk 30 and its crank pin 31 and thereby raise the slide 33, bringing the tail piece 38 of the contact member 35 into engagement with the end 39 of the cam plate 40. Continued upward movement of the slide 33 causes the arm 35 to swing from its full line position of Fig. 4 to the dotted line position therein bringing the friction member 37 into engagement with the under side 10 of the link 12. The slide 33 and arm 35 then continues upwardly carrying said link 12 to its uppermost position, when further opening movement of the doors other than that produced by the momentum of the moving parts toward their stops, ceases but continued rotation of the disk 30 carries the crank pin back to its starting point where it preferably comes to rest, and the contact member 35 returns to its collapsed position shown in 20 full lines in Fig. 4.
- The initial opening movement of the gate or doors 8 which starts the collapsing of the toggle links 11 and 12 thereby unlocking the door, permits the spring 60 shown most clearly in Fig. 3, to urge the collar 61 toward the stop 59 and, during this initial movement, the sliding rod 58 will be held by its spring in contact with the jamb of the elevator shaft opening 6.
- 30 The lever 53 moves bodily with the door but is rocked upon its pivot when the rod 58 is permitted to move in its guide or the door opens and this relative movement causes the arm 44 to be swung downwardly 35 from the upper folded position to its channel interlocking position whereupon continued movement of the door 8 will cause the gate to be fully collapsed moving conjointly with said door 8. If it is desired to retain the door in its open position, the operator may, by pressure upon the handle 17, retain the same in such position and when further need of this is removed, a release of said arm will, in the present example, cause the 40 toggle composed of the links 11 and 12, to be straightened by pressure exerted thereon by the spring 22 contained in the cylinder 18, thereby providing a self closing means for the elevator shaft door as well as for the 45 car closure means. As the door 8 approaches the end of its closing movement the forward end of the sliding member 58 will contact with the edge 62 of the door jamb and be depressed, thereby swinging the lever 53 upon its pivot downwardly and drawing with it the rod 51 which is attached by the crank arm 50 to the arm 44. By this movement 50 the arm 44 will swing upwardly bringing the uppermost roll 48 into engagement with the plate 63 and cause the cross arm 47 to swing about its axis against the action of the spring 49 to its folded inoperative position shown in dotted lines in Figs. 2 and 3 where it will remain so long as the toggle composed 55 of links 11 and 12 is in its straightened position wherein it serves as a lock to prevent operation of the elevator shaft door from the outside.
- While I have herein shown and described merely for illustrative purposes one specific embodiment of my invention and have disclosed and discussed in detail the construction and arrangement incidental to such disclosure, it is to be distinctly understood that the invention is limited neither to the mere 70 details or relative arrangement of the parts nor to the specific application herein shown, but that extensive variations from the illustrations may be made without departing from the principles thereof.
- Claims:
1. An elevator system comprising in combination, an elevator car, a plurality of floor openings, barriers for said openings, manually operable toggle means for operating said barriers, power means operable when said car is opposite a floor opening directly to operate upon said toggle means to move said barrier and spring means for closing said barrier.
  2. An elevator system comprising in combination, an elevator car arranged for movement to loading and unloading relation with a plurality of floor openings, closure means for said floor openings, manually operable toggle means for said closure means and power means carried by said car and normally out of engagement with said manual means adapted to be moved into operative engagement with said toggle when the car is within range of one of said floor openings to operate said closure means.
  3. In an elevator system, in combination, an elevator car, closure means for said car, an elevator shaft door, manual operating means for said door and power means carried by said car adapted to be moved from a normally withdrawn position to engage said manual operating means to effect the simultaneous operation of said door and closure means.
  4. In an elevator system, the combination with manually operable self-closing elevator shaft door operating means, of an elevator car and a motor driven power unit adapted to operate through said shaft door operating means to open said door.
  5. The combination with an elevator shaft door having self locking manual opening means, of an elevator car, power means carried by said car and operable at the will of the operator directly to unlock and to open said door.
  6. An elevator system comprising an elevator shaft door, manual operating means for said door including a pair of pivotal links 11 and 12, a hand operating lever 17 for said links a normally retracted contact member 35 and power means operable at the will of the operator to cause said contact

member to engage and move said link 12 to operate said door.

7. In an elevator system in combination, a car, a door, manually operable toggle means for opening said door and for locking said door in closed position, spring means for closing said door and locking said toggle, and motor driven means adapted to act upon said toggle means to operate said door.

8. An elevator system comprising an elevator car; closure means for said car arranged for manual operation to and from its open position; a shaft door; self-locking hand-operable means for opening said door; and electrically operated power means operable at the will of the operator of the car to effect the unlocking of said hand-operable means and the subsequent operation of said shaft door and acting therethrough to open said closure means.

9. An elevator system comprising, in combination, an elevator shaft door, an elevator car, a door for said car, manually operable means for opening one of said doors, spring means for closing said door, electric motor means for closing said door, electric motor operated means normally disconnected from said manually operable means arranged to

be operated at the will of the operator to act upon said manually operable means to open said door and means automatically to effect the interlocking of said doors, whereby both may be opened simultaneously by said electric motor operated means or said manual means and closed by said spring means.

10. An elevator system comprising, in combination a car, a door, manually operable opening means for said door, spring means for closing said door, power means carried by said car and means operable at will to operatively connect said power means with said manually operable means to operate the same by power.

11. In combination, a door, manually operable toggle means for opening said door and for locking said door in closed position, electrically operated means normally disconnected from said toggle means adapted to be moved operatively to engage said toggle to unlock and open said door, and spring means to actuate said toggle to close said door.

In testimony whereof, I have signed my name to this specification.

JOSEPH R. JACKSON, JR.

member to engage and move said link 12 to operate said door.

7. In an elevator system in combination, a car, a door, manually operable toggle means for opening said door and for locking said door in closed position, spring means for closing said door and locking said toggle, and motor driven means adapted to act upon said toggle means to operate said door.

8. An elevator system comprising an elevator car; closure means for said car arranged for manual operation to and from its open position; a shaft door; self-locking hand-operable means for opening said door; and electrically operated power means operable at the will of the operator of the car to effect the unlocking of said hand-operable means and the subsequent operation of said shaft door and acting therethrough to open said closure means.

9. An elevator system comprising, in combination, an elevator shaft door, an elevator car, a door for said car, manually operable means for opening one of said doors, spring means for closing said door, electric motor operated means normally disconnected from said manually operable means arranged to

be operated at the will of the operator to act upon said manually operable means to open said door and means automatically to effect the interlocking of said doors, whereby both may be opened simultaneously by said electric motor operated means or said manual means and closed by said spring means.

10. An elevator system comprising, in combination a car, a door, manually operable opening means for said door, spring means for closing said door, power means carried by said car and means operable at will to operatively connect said power means with said manually operable means to operate the same by power.

11. In combination, a door, manually operable toggle means for opening said door and for locking said door in closed position, electrically operated means normally disconnected from said toggle means adapted to be moved operatively to engage said toggle to unlock and open said door, and spring means to actuate said toggle to close said door.

In testimony whereof, I have signed my name to this specification.
